UNITED STATES PATENT OFFICE.

WILLIAM H. CLOPTON, OF WASHINGTON, DISTRICT OF COLUMBIA.

SCREW-LOCK.

1,350,139.

Specification of Letters Patent. Patented Aug. 17, 1920.

Application filed November 25, 1919. Serial No. 340,446.

To all whom it may concern:

Be it known that I, WILLIAM H. CLOPTON, a citizen of the United States, residing at Washington, in the District of Columbia, 5 have invented new and useful Improvements in Screw-Locks, of which the following is a specification.

It is often desirable when employing screws as fastening means to insure against 10 their accidental loosening or removal, and it is object of this invention to provide a device which, while being simple in character and consequently economical to manufacture, will satisfactorily serve this purpose 15 and may be readily employed in connection with screws of the usual type without, in any way, mutilating the screw to adapt it to the lock.

In the accompanying drawings in which 20 are shown two forms which my invention may take, it being understood that the invention may be embodied in other forms,

Figure 1 is a top plan view of my lock showing it as used with a screw,

Fig. 2 is a sectional view taken on the line 25 2-2 of Fig. 1,

Fig. 3 is a bottom plan view of the lock detached from the screw,

Fig. 4 is a top plan view of the lock 30 shown in Fig. 1 detached from the screw,

Fig. 5 is a vertical sectional view of a modified form of lock, and

Fig. 6 is a bottom plan view of the form 35 shown in Fig. 5.

Referring to the drawings in more detail and having particular reference to Figs. 1 and 2, 10 indicates a screw having the usual flared head 9 adapted to be countersunk in the work W.

40 A lock is shown as a washer-like annulus 1 adapted to be countersunk in the work so that its surface lies flush with the material into which the screw is to be inserted, and is provided with means for holding it in 45 fixed position, the means employed, in this instance, being two laterally disposed wings 2. At substantially its center, the lock is provided with an opening 3 to receive the screw, and to provide a neat fit for the screw head, there is formed around the opening, a 50 countersink 4.

As shown in Fig. 2, the lock has located

thereon an upstanding flange 5, surrounding the countersink 4 and opening 3, and serving as the means to fixedly connect the 55 screw and the lock 1. The flange 5, as well as the entire lock member, may be formed of a relatively soft metal although, in order to serve the purpose of the present invention, it is only necessary that the flange be 60 formed of the soft metal. After the screw is placed in operative position, as shown in Fig. 2, a portion of the flange, at the end of the head slot 6 of the screw, may be superimposed on the screw head or, as shown 65 in Fig. 1, disposed within the head slot, this being done in any suitable manner, as by a chisel or the like.

In the form of my device shown in Fig. 5, the lock is provided with a tubular shank 70 7, which will serve to satisfactorily guide the screw into the work and thus afford a lock which may be found to be of more suitable structure in certain classes of work. In this form of my device, the wings 8 extend to the end of the shank but operate in 75 the same manner as in the form shown in Figs. 1 and 2.

It will be observed that I have provided a screw lock which will be very economical 80 to manufacture and will, by reason of its fixed connection to the work and the screw, insure the latter against accidental loosening and removal. It is, of course, understood that such modifications may be made 85 in the devices shown in the accompanying drawings as come within the scope of the following claims wherein I define my invention.

What is claimed is:

1. A lock for screws, having a countersink for a screw head, a member adapted to be inserted into the material into which the screw is to be placed, and an upstanding flange surrounding said countersink adapted 95 to have portions superimposed on the screw head.

2. A lock for screws comprising a shell to receive the screw head, a member for fixedly securing the shell in position, and 100 means adapted to be displaced into the screw head-slot.

3. A lock for screws comprising a shell to receive the screw head, a member for

fixedly securing the shell in position, and means adapted to be displaced into the screw head-slot, said means comprising an up-standing flange of relatively soft metal.

5. A screw lock consisting of a central countersink for the screw head, wings adapted to enter the work, and a flange of

relatively soft metal surrounding the countersink and adapted to have portions displaced over the screw head.

In testimony whereof I have hereunto set my hand.

WILLIAM H. CLOPTON.
